SPECIFICATION forming part of Design No. 11,862, dated July 13, 1880.

Application filed February 12, 1880. Term of patent 3½ years.

To all whom it may concern:

Be it known that I, WINTHROP L. JACOBS, of Jersey City, in the county of Hudson and State of New Jersey, have invented a new and 5 original Design for a Carpet, of which the following is a specification.

This invention relates to a new and original design for carpets, oil-cloths, and similar fabrics.

10 It consists in the novel grouping and configuration of figures, hereinafter more fully described.

The accompanying photograph illustrates a face view of a carpet having my new design.

15 A is an irregular figure having a border formed of straight lines, and within these straight lines are curved ornamented figures.

C is a group composed of small star-shaped flowers that are joined by stems.

20 D is an ornamented fan-shaped scalloped-edged figure supported on bars *a b*, and within the angle of the said bars is a pedestal, *d*, supporting a star-shaped figure, *e*.

E is a group composed of curved and 25 ornamented segments *f* and a vase, *f'*.

F is a group composed of branches of leaves and a star inclosed in an irregularly-shaped border, *g*.

30 G is a group composed of foliated branches *g'*, stars *h*, a scalloped and ornamented figure, *h'*, and a bar, *h''*, all of which are inclosed in a border, *i*.

H is a column rising from a base, *i'*, and supporting the foliated figures *j*.

35 I is a group composed of a semicircular curve, *K*, formed of leaves and buds, a right-angular border, *k'*, and a fan-shaped figure, *l*, supported in a V-shaped bracket, *m*. The stem of said bracket is highly ornamented with 40 floral designs *m'*.

J is a central vase-like figure rising from a base, *L*, which is ornamented with flowers *n*.

M is a group composed of a zigzag border, *o*, a rectangular figure, *p*, with one rounded 45 corner, and an enfoliated figure, *q*.

N is a group composed of two rectangular figures, *r*, laid across each other at right angles and inclosing a star or rosette, and a semicircular figure, *r'*, having a pendant, *s*.

50 O is a field having its ground covered with scroll-like branches of leaves and flowers.

P is a group composed of a semicircular figure, *t*, formed of nearly parallel lines, and

with its exterior edge ornamented with scallops and a pendant, *u*.

The background of the carpet, between the several groups and figures, is plain and preferably of one color.
